UNITED STATES PATENT OFFICE

2,448,687

LIQUID AND GAS TRANSFER IN
MERCURY SWITCHESErnst Walter Rickmeyer, Berkeley, Ill., assignor
to Jefferson Electric Company, Bellwood, Ill., a
corporation of Illinois

Application October 26, 1945, Serial No. 624,790

8 Claims. (Cl. 200—80)

1

The present invention relates to a mercury switch, and more particularly to a switch in which a cup-like element having relatively porous walls divides the switch envelope into two chambers. Mercury is normally contained in one of these chambers and, under certain conditions, is adapted to pass through the porous walls of the cup into the other chamber. In a mercury switch an envelope is usually provided with a pair of electrical conductors fastened thereto in such a manner as to be electrically connected through the medium of a pool of mercury contained in the switch envelope. One of the conductors is usually fastened to an electrode that projects into the envelope and into the pool of mercury therein. The mercury, in turn, is electrically connected to the other conductor so as to complete the circuit in the envelope. In order to break the circuit the contact between the mercury and the electrode is broken. This can be accomplished by moving the electrode out of the pool of mercury or by moving the pool of mercury away from the electrode so that the two are no longer in contact. The present invention pertains to a switch of the latter type, wherein the body of mercury is moved relative to a stationary electrode so as to break the electrical contact therebetween.

As previously mentioned, a cup-like element is used to divide the switch element into two chambers. The electrode and the mercury are normally disposed in one of these chambers with the electrode at least partially immersed in the mercury. In order to break the circuit the mercury is caused to flow or pass through the walls of the cup-like element into the second chamber to thereby lower the level of the mercury pool in the first chamber sufficiently to physically separate the mercury and the electrode. This passage of mercury through the walls of the cup-like element is accomplished under certain circumstances where the mercury is caused to apply sufficient force against the walls of the cup-like element to pass through the pores in said walls.

This force is induced by rotating the switch envelope about an axis so as to produce centrifugal force of the mercury against the porous walls of the cup-like element and the speed of rotation of the envelope will determine the rate of flow of the mercury through the walls.

A mercury switch of this type that is intended to operate at different speeds of rotation to provide different time delay features in breaking the circuit between the mercury and electrode, in the past have not been satisfactory at high speeds.

2

The reason for this is that the greater centrifugal force caused by high rotating speeds forces the mercury through the walls of the cup-like element too fast so as to cause the circuit to be broken before it is desired to do so.

The present invention is intended to overcome this difficulty and to provide a switch of this type that has dependable time delay characteristics both at low and high speeds of rotation.

The foregoing constitute some of the principal objects and advantages of the present invention, others of which will become apparent from the following description and drawings, in which

Fig. 1 is a longitudinal sectional view through a mercury switch and showing the cup-like element embodying the present invention;

Fig. 2 is an end elevation view of the mercury switch shown in Fig. 1, the view being taken at the left hand side of the device shown in Fig. 1;

Fig. 3 is a transverse sectional view through the mercury switch, the view being taken on the line 3—3 of Fig. 1;

Fig. 4 is a transverse sectional view through the bottom support for the cup-like element, the view being taken on the line 4—4 of Fig. 1;

Fig. 5 is a sectional view corresponding to Fig. 1 but showing a second embodiment of the present invention; and

Fig. 6 is a diagrammatical view of a mercury switch shown mounted on a revolvable disk.

Two specific embodiments of the present invention have been selected and will be described herein in compliance with Section 4888 of the revised statutes. It is recognized that many modifications will occur to one skilled in the art, and it is intended that such modifications may be made without departing from the intended scope of the invention.

Referring now to Fig. 1 the invention is shown in conjunction with a mercury switch generally indicated at 15 which comprises a switch envelope 16, closed at the bottom as at 17 and open at the top to receive an electrode 18 that projects through the open top into the envelope interior.

The electrode 18 is provided with a shoulder 19 against which rests an insulating washer 20. A second washer 21 is inserted between washer 20 and the rim portion 22 of the envelope 15 that surrounds the open end thereof. Additional washers 23, 24, and 25 surround the electrode 18 and cooperate with the rim portion 22 of the envelope 15 to support the electrode 18. Each of these washers 20, 21, 23, 24, and 25 comprises some suitable insulating material such, for example, as polystyrene. The upper end of the

53

electrode 18 is turned over as at 26 to provide a shoulder, and a washer 27 of good electrical conducting material is inserted between this last mentioned shoulder and the upper insulating washer 25. To this washer 27 is secured one of the electrical conductors 28, and the other electrical conductor 29 is secured to a ring member 30 that surrounds the envelope 16 and is held in electrical conducting relationship therewith.

The envelope 16 is provided with a shoulder portion 31 adjacent to the upper end thereof and a cup-like member 32 is disposed inside the envelope 16 between this offset portion 31 and the bottom 17 of the envelope 16. The bottom 17 of the envelope 16 is held in place by means of a turned over portion 33 of the side walls of the envelope 16 and a washer 34 is inserted between this over-turned portion 33 and the bottom 17 of the envelope. The cup-like member 32 is provided with outwardly projecting supporting members 35 (Figs. 1 and 4) that rest against the bottom portion of the envelope. In the preferred embodiment of the invention shown in Fig. 1, this cup-like element 32 has tapered side walls that are provided with alternate diagonally offset or stepped portions 36 and vertical portions 37 which merge into a bottom portion 38 of narrower diameter than the upper portion of the cup-like member 32. The side walls of this cup-like member 32 together with the bottom wall 38 comprise a porous metallic material so that mercury under certain circumstances may be forced through these walls. A sintered powdered nickel is a suitable material for the cup-like member.

In the normal operation of the mercury switch shown in Fig. 1, mercury is contained inside the cup-like member 32 in such a manner as to complete an electrical connection from the outer walls of the envelope 16 to the electrode 18. This mercury switch 15 may be mounted on a rotatable disk shown in Fig. 6 at 40. This disk 40 may be mounted on a shaft 41 so as to be rotatable thereabout. The mercury switch is shown at 15 in Fig. 6 disposed with its bottom wall 17 farthest removed from the center of the disk 40. As the disk 40 is rotating about the shaft 41, mercury that is disposed within the cup-like element 42 (Fig. 1) is forced by centrifugal force outwardly against the bottom 38 of the cup-like portion 32. As this centrifugal force reaches a predetermined amount corresponding to some pre-selected speed of rotation of the disk 40, the mercury is caused to flow through the bottom wall 38 of the cup-like member 32 into a separate chamber indicated at 42 in Fig. 1. The air in this chamber 42 thus displaced by the mercury is forced along the tapered sides of the cup-like member 32 and passes through the porous walls so as to equalize the pressures on both sides of the walls of the cup-like member.

During this rotation of the mercury switch 15 the step-like portions 36 of the walls of the cup 32 create turbulence in the flow of mercury so as to reduce the amount of mercury that would otherwise be disposed against the bottom wall 38 of the cup-like member 32. In this manner at high rotating velocities of the mercury switch 15 only a fraction of the mercury will be disposed against the lower face 38 of the cup-like member 32, the remainder of the mercury being held back against the side walls of the cup-like member by the turbulence. Thus the effects at high rotating speeds is minimized to the extent of the turbulence so as to reduce the rate of flow through the bottom wall 38 of the cup-like mem-

ber 32. At lower rotating speeds of the mercury switch 15, there is less turbulence in the flow of the mercury so that under these conditions a greater proportion of the mercury is disposed against the bottom wall 38 of the cup-like member 32. Thus at these lower rotating speeds a greater force is applied by the mercury against the bottom wall 38. Thus by means of creating turbulence in the mercury, compensating means are provided for differences in centrifugal force caused at different rotating speeds of the mercury switch.

In Fig. 5 a second embodiment of the invention is shown. In this arrangement the cup-like element is shown at 45 and has relatively straight sides 46 flared only at the top as at 47 and slightly tapered at the bottom at 48. Projecting inadequately from the walls of the cup-like member 45 are angular, incline baffle members 49. As shown, there are two of such members 49, the lower one of which is indicated at 49a and projects further into the cup-like member than the upper baffle member. These inadequately projecting members 49 and 49a produce the turbulence in the flow of the mercury in the manner previously described with respect to the first embodiment of the invention.

As shown in Fig. 4 the projections 35 at the bottom of the cup-like member 32 comprises a plurality of segments 35a spaced apart to provide passages therebetween through which the mercury may escape in the event that it is trapped between these segments 35a.

Having thus described my invention, what I claim as new and desire to secure by Letters Patent is:

1. In a mercury switch of the class described a switch envelope, a relatively porous cup in the envelope adapted to contain a body of mercury and dividing the envelope into two chambers, the mercury being adapted to flow from within the cup to the second chamber through the porous walls of the cup, said cup comprising tapered walls, and sloping means on the walls for causing turbulence in the flow of mercury from one chamber to the other.

2. In a mercury switch of the class described a switch envelope, a porous dividing wall in the envelope forming two separate chambers, the wall being cup shape with tapered walls, and sloping surfaces on the inner faces of the walls projecting into the cup.

3. In a mercury switch of the class described an elongated switch envelope, a porous cup in the envelope extending lengthwise thereof and having tapered walls, the cup dividing the envelope into two chambers, and inwardly projecting surfaces on the walls of the cup, said projections sloping toward the bottom of the cup.

4. In a mercury switch of the class described, a switch envelope, a porous cup in the envelope with its bottom disposed adjacent to one wall of the envelope, the sides of the cup at least for a portion of the length of the cup being spaced from the envelope walls so that the cup divides the envelope into two chambers, and inwardly projecting surfaces on the walls of the cup, the surfaces sloping toward the bottom of the cup.

5. In a mercury switch of the class described, a switch envelope in the form of a cylindrical shell, an inner porous cup having one end adapted to engage the inner face of the shell, the walls of the cup being tapered toward the other end of the cup, the walls of the cup being provided with

inwardly projecting surfaces sloping toward the cup bottom.

6. In a mercury switch of the class described, a switch envelope, a porous cup in the envelope with its bottom disposed adjacent to one end of the wall, the sides of the cup at least for a portion of the cup length being spaced from the envelope walls so that the cup divides the envelope into two chambers, the side walls of the cup comprising a plurality of cylindrical segments of progressively narrower diameter from one end of the cup to the other end of the cup, and tapered wall segments connecting adjacent segments.

7. In a mercury switch of the class described,

a switch envelope, a porous cup in the envelope with its bottom disposed adjacent to one end of the wall, the sides of the cup at least for a portion of the cup length being tapered toward the bottom of the cup, and a plurality of inwardly projecting porous baffle members supported by said walls, these baffle members sloping toward the bottom of the cup.

5 8. In a mercury switch of the class described, 10 a switch envelope, a dividing wall in the envelope in the form of a sintered metal cup having tapered walls, and sloping surfaces on the inner faces of the walls projecting into the cup.

ERNST WALTER RICKMEYER.
